ENDLESS GRATE STOKER COMPRISING AIR FEED AND SIFTINGS REMOVAL MEANS

Eric H. Smith and Oscar A. Johnson, Worcester, Mass., assignors to Riley Stoker Corporation, Worcester, Mass., a corporation of Massachusetts

Application February 25, 1946, Serial No. 649,980

4 Claims. (Cl. 110—40)

1

This invention relates to automatic stokers, and more particularly to stokers of the endless grate type having transversely extending compartments through which air is supplied under forced draft to the upper run of the grate.

In the operation of such stokers there is a tendency for a certain amount of the finer particles of the fuel to sift through the air openings in the grate and to become deposited in the air compartments. If these deposits of siftings are allowed to accumulate to any great extent they will not only obstruct the air flow but they may become ignited and cause serious damage to the stoker structure. Accordingly various constructions have been proposed for removing the siftings from the compartments, but in general the prior arrangements have been complicated and expensive, usually including many moving parts subject to wear or breakage. In some cases it has been impossible to remove the siftings without interrupting the operation of the stoker, or at least shutting off the flow of air to the various compartments successively.

It is accordingly one object of the invention to provide a forced draft endless grate stoker having a comparatively simple and inexpensive means for removing siftings from air compartments beneath the upper run of the grate.

It is a further object of the invention to provide a stoker of the aforesaid type having a siftings removal apparatus with a minimum of movable parts and capable of operating in an efficient and rapid manner without interfering with the normal operation of the stoker.

With these and other objects in view, as will be apparent to those skilled in the art, the invention resides in the combination of parts set forth in the specification and covered by the claims appended hereto.

Referring to the drawings illustrating one embodiment of the invention, and in which like reference numerals indicate like parts,

Fig. 1 is a longitudinal section through an endless grate forced draft stoker, the section being taken on the line 1—1 of Fig. 2;

Fig. 2 is a plan view taken in section on the line 2—2 of Fig. 1;

Fig. 3 is a section taken on the line 3—3 of Fig. 2;

Fig. 4 is a section taken on the line 4—4 of Fig. 1, at a somewhat larger scale; and

Fig. 5 is a fragmentary section taken on the line 5—5 of Fig. 4, at a considerably larger scale.

The embodiment illustrated comprises walls 10 forming a furnace or combustion chamber which is fired by an automatic stoker having an endless grate 11 supplied with fuel from a hopper 12 (Fig. 1) at the front of the furnace. The grate may be of any suitable and well-known construction, and as indicated in Fig. 4 it may include

2

a plurality of longitudinally extending endless chains 14, the upper run of each chain being carried by a track 15, the tracks being supported by transverse horizontal beams 16. These beams are preferably of a flanged cross section, such as I-beams, and their lower flanges support horizontal plates 18. This construction provides a plurality of transversely extending separate air compartments 19 beneath the upper run of the grate 11, the plates 18 forming the bottom walls of the compartments. Each compartment communicates at one end with a separate air box 21 having an access door 22 in its outer wall. Air under pressure is supplied to each box 21 by means of a separate duct 23 provided with a damper 24. As so far described the stoker construction is well-known in the art.

During the operation of the stoker some of the finer particles of fuel will drop through the grate into the air compartments, and the invention provides means for collecting and removing such siftings. For this purpose a transverse substantially horizontal pipe 26 is mounted within each compartment 19 and extends along the central portion of the bottom plate 18. These pipes are preferably of square or other rectangular cross section, and they are provided with openings 27 in their upper walls to receive the siftings. The inner ends of the pipes are preferably open to the atmosphere, and their outer ends are connected by branch pipes 28 to a main header 30 leading to a suitable suction-producing device, such as an ejector, fan, or the like (not shown). Each branch pipe 28 is provided with a slide valve 31. The entrance openings 27 in the pipes 26 are controlled by slide plates 33 which rest on the tops of the pipes and have openings 34 arranged to register with the pipe openings 27 when the plates are moved outwardly. As illustrated, each pipe 26 supports two of the slide plates 33, each plate having an operating rod 35 which extends outwardly and upwardly through the outer wall of the corresponding air box 21. Lugs 36 (Fig. 4) project upwardly from the plates 33.

The invention provides means to direct the accumulating siftings toward the pipe openings 27. The preferred construction for this purpose comprises a pair of plates 38 extending lengthwise of each air compartment 19 in a downwardly converging or V-shaped arrangement. The upper edges of these plates are secured to flanges 39 which project laterally from the beams 16, and the lower portions of the plates are connected by brackets 40 (Fig. 5) to the pipe 26. The lower edges of the plates are slightly spaced apart to provide a slot in registration with the openings 27, and they are located closely above the slide plates 33. Each plate 38 is provided with openings 42 near its upper edge to permit flow of

combustion air upwardly therethrough, these openings preferably being located beneath the grate tracks 15 as shown in Fig. 4. It will be clear from Fig. 4 that the space between each pair of plates 38 is fully open at one end for the direct reception of air entering the corresponding air compartment 19, so that part of the air will flow above the plates while part will flow beneath the plates and thence upwardly through the openings 42. Thus the entire cross-sectional area of the air compartment is available for air flow, and the air will be distributed very uniformly across the stoker.

The operation of the invention will now be apparent from the above disclosure. The grate 11 will be supplied with fuel from the hopper 12, and combustion will take place as the fuel bed moves slowly to the rear. Air for combustion will enter the compartments 19 from the ducts 23 and the air boxes 21, under the control of the dampers 24. Some of the air will enter beneath the plates 38 and flow upwardly through the openings 42. Fine fuel which sifts through the grate will collect in the V-shaped trough or hopper formed by the plates 38. The tracks 15 will shield the openings 42 from the falling siftings. The valves 31 are normally closed, and the openings 21 are normally closed by the slide plates 33. When the operator wishes to clean out the siftings from a particular compartment, he will open the corresponding valve 31 and pull one of the slide plates 33 outwardly by means of its rod 35, thus uncovering the openings 27. During this movement of the slide plate the lugs 36 will break up any arches which may have formed in the siftings. The siftings will now enter the openings 27 under the combined effect of gravity, the air pressure within the compartment, and the suction within the pipe 26. A strong current of air will enter the open end of the pipe 26 and carry the siftings along the pipe, and through the corresponding branch pipe 28 and the pipe 30 to a suitable place of disposal. Preferably they are eventually returned by some means to the furnace for combustion therein. Only a very brief time will be required to discharge the siftings above one slide plate 33, whereupon this plate will be closed and the other slide plate in the same compartment will be opened for the necessary interval. As soon as the cleaning of a compartment is completed, the corresponding valve 31 will be closed, and another compartment may be cleaned in the same manner. The removal of siftings is accomplished expeditiously and without in the least interfering with the normal operation of the stoker. The construction is simple and inexpensive, and free from moving parts subject to wear and breakage.

Having thus described our invention, what we claim as new and desire to secure by Letters Patent is:

1. An automatic stoker comprising an endless grate having an upper run to support a fuel bed, transverse beams dividing the space beneath the upper run of the grate into a plurality of separate air compartments, plates extending between the beams to form the bottom walls of the compartments, a transversely extending pipe within each compartment and adjacent the bottom wall thereof, the pipes having openings in their upper walls for the admission of fine fuel siftings, a pair of downwardly converging plates within each compartment to direct the siftings toward the pipe, means to supply air to one end of each com-

partment, the said converging plates having openings in their upper portions for the upward flow of air therethrough and the space between each pair of converging plates being open at one end for the direct reception of air entering the corresponding air compartment, a suction header, and branch pipes connecting one end of each pipe to the header.

2. An automatic stoker comprising an endless grate having an upper run to support a fuel bed, transverse beams dividing the space beneath the upper run of the grate into a plurality of separate air compartments, plates extending between the beams to form the bottom walls of the compartments, a transversely extending pipe within each compartment and adjacent the bottom wall thereof, the pipes being of rectangular cross section with flat upper walls provided with openings therein for the admission of fine fuel siftings, valve plates resting on the said upper walls and slide longitudinally of the pipes to control the openings, a pair of downwardly converging plates within each compartment to direct the siftings toward the pipe, a suction header, and branch pipes connecting one end of each pipe to the header.
3. An automatic stoker comprising an endless grate having an upper run to support a fuel bed, transverse beams dividing the space beneath the upper run of the grate into a plurality of separate air compartments, plates extending between the beams to form the bottom walls of the compartments, a separate air box at the outer end of each compartment to supply air thereto, a transversely extending pipe within each compartment and adjacent the bottom wall thereof, the pipes being of rectangular cross section with flat upper walls provided with openings therein for the admission of fine fuel siftings, valve plates resting on the said upper walls, rods extending outwardly from the valve plates and through the air boxes to slide the valve plates along the pipes and thus control the openings, a pair of downwardly converging plates within each compartment to direct the siftings toward the pipe, a suction header, and branch pipes connecting one end of each pipe to the header.

4. An automatic stoker as covered by claim 1 in which spaced longitudinally extending tracks are provided to support the upper run of the grate, and the air openings in the converging plates are located beneath the said tracks.
